WEAR INDICATING DEVICE FOR DRILL BITS

Daniel L. Del'Homme, Houston, Tex., assignor to
Reed Roller Bit Company, Houston, Tex., a cor-
poration of Texas

Application September 22, 1949, Serial No. 117,128

6 Claims. (Cl. 255—61)

1

This invention relates to new and useful im-
provements in wear indicating devices for drill
bits.

In well drilling, maximum efficiency is obtained
when the drill bit which is attached to the lower
end of the drill pipe is used until it is substan-
tially dull and is no longer capable of performing
the drilling operation. It has heretofore been
the practice to rely solely upon the driller and
his particular knowledge based upon experience
with respect to the time when the drill bit has
dulled and should be removed, and obviously the
human element of error has always been present
with the result that in many instances the bit
has been "pulled" or removed from the well pre-
maturely or too long after the drilling bit has lost
its efficiency.

It is one object of the present invention to pro-
vide an improved indicating device which will
automatically signal to the surface when the drill
bit is worn to a predetermined point whereby ac-
curate information as to the condition of the
drill bit is made known to the driller or operator.

An important object of the invention is to pro-
vide a wear indicating device for drill bits where-
in the pressure of the drilling fluid is utilized
as a signalling medium and also wherein a sud-
den variation in said pressure is indicative of the
fact that the bit has been worn to a predeter-
mined point.

A further object is to provide a device, of the
character described, wherein a fluid discharge
opening is normally sealed by a movable valve
element, together with means actuated when the
drill bit wears to a predetermined point for per-
mitting the valve member to open the discharge
port and thereby cause a pressure variation in
the circulating fluid which will function to sig-
nal the opening of said port and the wear of the
bit to the surface.

Still another object is to provide an improved
indicating device which may be readily applied
to a drill bit of ordinary construction and which
includes a piston-like valve member normally
closing a discharge outlet, together with liquid
means for maintaining the piston valve in a pos-
ition closing said outlet; wear of the bit to a pre-
determined point releasing the liquid means to
allow movement of the piston valve and opening
of the discharge outlet.

Other and further objects of the invention will
appear from the description of the invention.

In the accompanying drawings, which form a
part of the instant specification, which are to
be read in conjunction therewith, and wherein

2

like reference numerals are used to indicate like
parts in the various views:

Figure 1 is an elevation of the drill bit having
the improved indicating device constructed in ac-
cordance with the invention mounted thereon.

Figure 2 is a bottom view of the drill bit.

Figure 3 is an enlarged longitudinal sectional
view taken through the indicating device and
illustrating the piston valve in a position closing
the discharge outlet, and

Figure 4 is a view similar to Figure 3 with the
piston valve in a position opening said outlet.

In the drawings the numeral 10 designates a
bit body which has the usual threaded box 11 at
its upper end whereby the bit may be connected
to the lower end of a drill pipe or stem A. The
usual fluid cavity or chamber 12 is formed in the
bit body and cutting blades 13 are welded or
otherwise secured to the lower portion of said
body. Drilling fluid circulating passages 14 ex-
tend from the cavity 12 and discharge from the
lower portion of the body adjacent the blades 13
(Figure 2). As illustrated the blades 13 are dis-
posed transversely of the bit body and have their
lower cutting edges 13a located in a plane below
the lower end of the body. When the cutting
blades have been worn through the drilling op-
eration to approximately the line indicated at B
in Figure 1 or their vertical or reaming edges
have been worn to the line indicated at C in this
figure, it is desirable that the bit be replaced for
at such time the bit is completely dulled.

For indicating that the bit blades 13 are worn
either to the point B or the point C the improved
indicating device D is arranged to be mounted on
the bit body. As is clearly shown in Figures 3 and
4, the device includes a tubular cylinder 15 having
an axial bore 16 extending entirely therethrough.
The upper end of the cylinder is threaded into an
elbow 17 and communicates with the bore 18 of
said elbow. The lateral leg of the elbow 17 is ar-
ranged to be threaded within an opening 19 which
is formed in the wall of the bit body and which
communicates with the fluid cavity or chamber 12
of the bit. The cylinder 15 has a plurality of dis-
charge openings or outlets 20 provided in its up-
per portion and said outlets establish communica-
tion between the bore of the cylinder and the
well bore E within which the bit is disposed.

For controlling the flow of drilling fluid which
is normally circulated downwardly through the
drill pipe A and into the chamber of the bit out-
wardly through the elbow 17 and outlets 20, a
cylindrical valve member 21 is slidable within
the bore 16 of the cylinder 15. A sealing ring 22

is mounted at each end of the valve member 21 and seals with the bore 15 of the cylinder. When the valve member is in its raised position as shown in Figure 3, said member functions to close the outlet ports 20 and thus the drilling fluid circulating through the chamber or cavity 12 of the bit body cannot escape outwardly through said outlets; however, when the valve member 21 is moved downwardly as shown in Figure 4 the drilling fluid from within the cavity 12 may pass outwardly through the elbow 17 into the upper portion of the cylinder 15 and then outwardly through the openings or outlets 20 in the wall of said cylinder. The cross-sectional area of the discharge openings or outlets 20 are at least equal to the bore 15 of the connecting elbow 17 which is in itself relatively large, whereby when the valve is moved downwardly as shown in Figure 4, a very noticeable pressure drop will occur in the pressure of the circulating fluid.

For locking the valve member 21 in its raised position until such time as the bit blades 13 are worn to either of the dotted lines B or C, the lower portion of the cylinder is adapted to receive a liquid medium. This liquid is retained within the lower portion of the cylinder and also within a wear tube 23 which has its lower end closed and its upper end threaded into a coupling collar 24 which collar is threaded onto and closes the lower end of the cylinder. The liquid is adapted to be introduced into the cylinder below the valve member and into the wear tube through a back check valve 25 which is mounted in the lower portion of the wall of the cylinder 15. It is evident that when liquid is introduced through the check valve 25 such liquid will drive the valve member 21 to its uppermost position against an abutting shoulder 17a formed within the connecting elbow and said liquid will entirely fill the lower portion of the cylinder and the interior of the wear tube 23. It is evident that said liquid will thereby lock the valve against downward movement within the cylinder.

The wear tube 23 is located contiguous to the outer surface of the bit body and extends to a desired point with respect to the bit blades 13. As shown in Figure 1, the closed end of the wear tube is located at substantially the point of intersection between the dotted lines B and C which are the points of wear of the bit blades at which a signal is desirable.

In the operation of the device, the indicator unit D is mounted on the external surface of the bit body and a suitable liquid is introduced through the check valve 25 to move the valve member 21 to its uppermost position and to thereby lock the same against downward movement within its cylinder. In such position the valve member 21 closes the discharge outlets 20 in the wall of the cylinder. With the valve member closing the discharge outlets 20 the bit is lowered in the usual manner into position and the drilling operation proceeds.

As the bit is worn either to the point B or to the point C in Figure 1, the abrading action of the formation against the lower end of the wear tube 23 results in a wearing away of said closed end, whereby the wear tube is opened and the liquid which normally locks the valve member 21 in its upper position is released. The drilling fluid is, of course, being constantly circulated downwardly through the drill stem and chamber 12 and is normally discharged through the passages 14 against the bit blades, and this drilling

fluid is, of course, under a predetermined or known pressure. As soon as the wear tube 23 has its end worn away and the liquid locking the member in its raised position is released, the valve member is caused to move downwardly by the pressure of the circulating drilling fluid which is constantly acting against its upper end through the connecting elbow 17. As the valve member is moved downwardly to the position shown in Figure 4 the discharge outlets 20 are uncovered and thus, the circulating drilling fluid may escape through said outlets. Because the size of the outlets is substantial the sudden opening of the outlets 20 results in a sudden or abrupt pressure drop in the pressure of the circulating drilling fluid and this pressure drop is an immediate indication to the operator that the wear tube 23 has been opened which means that the bit blades 13 have worn to a predetermined point. Thus an indication is provided at the surface that said bit requires replacement.

It is pointed out that the wear tube 23 is closely confined against the external surface of the bit body and extends contiguous to the rear surface of one of the blades 13 so that under normal drilling it is protected against undue wear and premature abrasion which would release the liquid. The invention is shown as applied to the usual blade type drill bit but it is apparent that said bit may readily be employed with any of the ordinary bits now in general use. It is also noted that the end of the wear tube may be located in any desired plane so that the signal is given when the bit wears to a predetermined point.

From the foregoing it will be seen that this invention is one well adapted to attain all of the ends and objects hereinabove set forth, together with other advantages which are obvious and which are inherent to the structure.

It will be understood that certain features and subcombinations are of utility and may be employed without reference to other features and subcombinations. This is contemplated by and is within the scope of the claims.

As many possible embodiments may be made of the invention without departing from the scope thereof, it is to be understood that all matter herein set forth or shown in the accompanying drawings is to be interpreted as illustrative and not in a limiting sense.

Having described the invention, I claim:

1. In combination, a drill bit having cutting elements thereon and also having an opening in its wall, means for circulating a pressure drilling fluid through said bit, a movable valve having one end exposed to the pressure of the drilling fluid and movable relative to the opening for controlling flow through said opening, a closed chamber having a liquid therein and having the opposite end of said valve exposed to said liquid, whereby said liquid functions to lock said valve against movement and in a position closing the opening, and means normally closing the chamber and adapted when opened to release the liquid from the chamber, the chamber closing means comprising a wear element on the exterior of the body which is located to be contacted by the formation when the cutting elements of the bit are worn down to a predetermined point, whereby the fluid in the chamber may escape and the circulating drilling fluid may move the valve to an open position to permit said circulating fluid to discharge through the opening to

thereby vary the pressure of the drilling fluid within the bit.

2. In combination, a drill bit having cutting elements thereon and also having an opening in its wall, means for circulating a pressure drilling fluid through said bit, a movable valve having one end exposed to the pressure of the drilling fluid for controlling flow through said opening, a closed chamber having a liquid therein and having the opposite end of said valve exposed to said liquid, whereby said liquid functions to lock said valve against movement and in a position closing the opening, a wear tube extending from the liquid chamber and having its outer end closed and located exteriorly of the bit adjacent one of the bit blades, said outer end being adapted to be abraded away when the cutter elements of the bit have worn to a predetermined point during a drilling operation to release the liquid from the chamber and thereby permit movement of the valve to an open position allowing flow of drilling fluid through the opening in the bit.

3. The combination with a drill bit having cutter elements and having an opening in its wall, of a wear indicating assembly including, a cylinder having one end communicating with the opening in the bit and its opposite end closed, said cylinder having a discharge outlet in its wall intermediate its end, a valve slidable in the cylinder and movable to positions closing or establishing flow from the opening in the bit to the discharge outlet in said cylinder, means for introducing a liquid into the cylinder between the valve and the closed end of the cylinder to move the valve in a position shutting off flow to the discharge outlet and to normally lock the valve against movement from such position, and means mounted in the wall of the cylinder and disposed exteriorly of the bit body for opening the closed end of the cylinder when the cutting elements have worn to a predetermined point during a drilling operation to release the locking liquid

and allow the valve to move within the cylinder and thereby establish communication between the opening and discharge outlet.

4. The combination as set forth in claim 3, wherein the means for opening the closed end of the cylinder comprises a wear tube communicating with the cylinder and extending therefrom, the free end of said tube being normally closed to confine the locking liquid and being disposed exteriorly of the bit body whereby it may be abraded away by the formation within which the drill bit is performing a drilling operation.

5. The combination as set forth in claim 3, wherein the means for opening the closed end of the cylinder comprises a wear tube communicating with the cylinder and extending therefrom, the free end of said tube being normally closed to confine the locking liquid and being adapted to be abraded away by the formation within which the drill bit is performing a drilling operation, said wear tube extending contiguous to the outer surface of the bit body and having its closed end terminating in a predetermined plane with respect to the cutting elements of the bit, whereby said tube is opened when said cutter elements have worn to a predetermined point.

6. The combination as set forth in claim 3, wherein the means for introducing the liquid within the cylinder is a back check valve mounted in the wall of the cylinder.
